[57] **CLAIM**

The ornamental design for a hair rinsing cap, as shown and described.

DESCRIPTION

FIG. 1 is a perspective view of a hair rinsing cap showing my new design;

FIG. 2 is a left side elevational view thereof;

FIG. 3 is a front elevational view thereof the side opposite being a mirror image of the side shown;

FIG. 4 is a rear elevational view thereof;

FIG. 5 is a top plan view thereof; and,

FIG. 6 is an enlarged fragmentary perspective view of the inlet hose of FIG. 1.

The hose and pipe portions are shown partially broken away to indicate indeterminate length. The undisclosed portions of the underside of the cap follow the configuration and detailing of the portion shown.

The partially disclosed inlet hose element is of conventional shape.
